UNITED STATES PATENT OFFICE.

PAUL E. OSWALD, OF LOS ANGELES, CALIFORNIA.

ELECTRIC FLAT-IRON AND CONDUCTOR.

No. 888,843.

Specification of Letters Patent.

Patented May 26, 1908.

Application filed March 14, 1907. Serial No. 362,276.

To all whom it may concern:

Be it known that I, PAUL E. OSWALD, a citizen of the United States, residing at Los Angeles, county of Los Angeles, State of California, have invented new and useful Improvements in Electric Flat-Irons and Conductors Therefor, of which the following is a specification.

Heretofore in the construction of electric flat irons it has been customary to inclose the conductor within a case having a very thin bottom with but little metal between the smoothing surface of the iron and the conductor so that the iron would become quickly heated on its smoothing surface. It frequently happens that in this construction the smoothing surface becomes overheated and when the current is off it quickly cools. Conductors have been used which are subject to being burned out.

It is one of the objects of my invention to produce an iron in which there is a considerable quantity of metal integral with the smoothing surface and to inclose the electric conductor in a vertical channel near the outer edge of the iron and insulated therefrom by a layer of heat resisting material which is a non-conductor and is molded to fit the conductor, and which will protect the conductor against undue strain, and which can be handled with the conductor.

Another object of my invention is to produce a conductor of high resistance, of cheap material, of great uniformity, of but little bulk, and which will not burn out.

I accomplish these objects by the iron described herein and illustrated in the accompanying drawings in which:

Figure 1—is a central longitudinal section of the top case or upper portion of the iron, the body of the iron being shown partly in central section and partly in elevation with a portion of the conductor shown in elevation. Fig. 2—is a plan with the top case removed. Fig. 3—is a rear end elevation. Fig. 4—is a cross section on the line 4—4 Fig. 1. Fig. 5—is a fragment of the conductor.

In the drawings 6 is the body of the iron, the bottom of which forms the smoothing or ironing surface. The smoothing surface projects beyond the main body and is rather thin in this projecting edge, which I will call ledge 7, upon which rests a washer of asbestos 8 or other electric and heat insulating material. This washer exteriorly is of the

configuration of the ledge and interiorly fits the body of the iron. Above this washer and surrounding the body of the iron is a thin layer of insulating material 9, which is preferably a sheet of mica. Surrounding the mica is the conductor 10 which is preferably formed of compressed graphite. This conductor is formed in the following manner; the graphite or other material is mixed with liquid paraffin or other volatile material to form a plastic mass. It is then put under pressure to squeeze out as much of the paraffin as is practical. It is then put into a mold of the configuration to fit into the device in which it is to be used. In the iron it fits around the sheet of mica on the body of the iron, and is formed into a thin ribbon having staggered slits 11 therein extending from opposite sides, as best shown in Figs. 1 and 5. The ribbon may then be put into an oven and the paraffin burned out, or it may be burned out in any other manner. This leaves the conductor a very compact and hard ribbon. Where a very great pressure, say 1,000 pounds or more to the square inch, is used paraffin or other volatile material may be omitted. The slits may then be filled with a plastic insulating compound and when dry the ribbon is ready for use. It is then placed in position around the sheet of mica. It will be observed that the ribbon is not continuous but the ends thereof are slightly separated at the rear end of the iron, and each end is provided with a metallic contact strip 12, the upper ends of which project above the top of the ribbon and are slightly resilient and are insulated from the body. A continuous vertical washer of insulating and heat resisting material 13 is then placed around the conductor, and the top of the same and the parts which it surrounds is covered with a sheet of asbestos 14 or other heat and electric insulating material. The top case 15 is then secured to the body by means of screws 16 and 17, the one nearest the front of the iron being counter-sunk so as to leave the top at this point smooth. At the rear end of the top case, and preferably cast integral therewith, is a standard 18 to which the handle 19 is fastened by bolt 20. To the rear end of the top case are secured the contact posts 21 for the reception of the wiring plug which connects the iron to the source of electrical energy. These posts are insulated from the

cover. The lower end of these contact posts engage the upper ends of the contact strips

12. I prefer after the conductor ribbon has been compressed to put it into a mold of a 5 configuration to form the vertical insulating washer which lies exterior the ribbon. This washer I prefer to form of plastic material and as it is being formed the material will be pressed so that it will enter the interstices 10 in the ribbon. The ribbon and washer can then be put into an oven and the washer dried and the paraffin burned out of the ribbon thereby making a closer contact between the ribbon and washer than if formed 15 separately.

Having described my invention what I claim is:

1. An electric flat iron having a vertical channel around the edge thereof, and an 20 insulated compressed graphite conductor in said channel.

2. An electric flat iron having a vertical channel around the edge thereof, an insulated 25 compressed graphite conductor in said channel; and a heat insulating vertical

washer in said channel exterior said conductor.

3. An electric flat iron comprising a body having a ledge at the bottom thereof, a heat and electric insulating washer on said ledge, 30 a sheet of insulating material above said washer and around said body, a compressed graphite ribbon having staggered slits in its opposite sides exterior said insulating material, contacts secured to the ends of said 35 ribbon, heat and electric insulating material exterior said ribbon and within said slits, heat and electric insulating material upon said body and conductor, a cover for said body and conductor having a handle secured 40 thereto and contact posts secured to and insulated from the cover and engaging the contacts secured to the conductor.

In witness that I claim the foregoing I have hereunto subscribed my name this 6th 45 day of March, 1907.

PAUL E. OSWALD.
